UNITED STATES PATENT OFFICE

OSCAR ERICKSON, OF ALEXANDRIA, MINNESOTA

LINE FOLLOWER

Application filed May 15, 1928. Serial No. 277,910.

This invention relates to a line follower and one object of the invention is to provide a device which may be applied to a sheet of paper, record book or other stationery of a like character, with an arm extending across a sheet so that when copying or reading data written or printed upon a sheet a line of writing or figures may be easily followed across the sheet and danger of missing a line of writing or not properly reading the same across a sheet prevented.

Another object of the invention is to provide the device with a body portion having cooperating jaws whereby the device may be firmly clamped to one side portion of a sheet of paper or book to which the device is to be applied and thereby firmly hold the device in place.

Another object of the invention is to provide the device with an improved type of arm for extending across a sheet beneath lines of writing thereon and permit the arm to be adjusted longitudinally so that it may accommodate itself to the width of the sheet.

Another object of the invention is to connect the arm with a carriage movable longitudinally upon a track carried by the body portion of the device so that the arm may be shifted towards the top or the bottom of the sheet and thereby disposed beneath a selected line of writing and easily moved from one line to another.

Another object of the invention is to provide improved means for shifting a carriage for the indicating arm longitudinally of a track carried by the body portion of the device and so construct this actuating means for the carriage that it may also serve to retain the carriage in a set position.

Another object of the invention is to provide the device with a body portion having jaws capable of gripping either a single sheet of paper or a number of sheets placed in a stack or bound in a book.

The invention is illustrated in the accompanying drawing, wherein

Figure 1 is a top plan view showing the device applied to a book with the book opened and the arm extending across a page thereof;

Fig. 2 is a transverse sectional view taken on the line 2—2 of Fig. 1, and

Fig. 3 is a perspective view of the carriage with elements carried thereby removed.

The body portion of the improved line follower consists of upper and lower plates 1 and 2 formed of sheet metal and normally held in flat contacting engagement with each other by springs 3 disposed about pins 4. The pins are carried by the lower plate and may consist of bolts passed upwardly through aligned openings in the two plates with their heads bearing against the under surface of the lower plate or they may be welded or otherwise rigidly secured to the lower plate and project upwardly through openings in the upper plate. Nuts 5 are threaded upon the upper end portions of the pins and engage washers 6 which bear against the springs, and it will be readily understood that by adjusting the nuts upon the pins the springs may be tensioned to yieldingly retain the upper plate in close contacting engagement with the lower plate without sufficient pressure being applied to make it difficult to move the upper plate away from the lower plate. Handles 7 and 8 which are substantially U-shaped are provided for the two plates and extend outwardly therefrom with the lower handle curved, as shown in Fig. 2, so that when the lower plate and its handle are resting upon a table or other support and pressure is applied to the upper handle the plate 1 may be easily swung upwardly away from the lower plate for insertion or removal of sheets or pages of a book. When a sheet of paper or the pages of a book are inserted between the upper and lower plates and pressure removed from the upper handle, the springs will again force the upper plate downwardly and the sheets of paper will be firmly gripped between the arms 9 of the upper plate and corresponding side portion of the lower plate.

The carriage 10, which is illustrated in Fig. 3, consists of a tubular body 11 which fits loosely upon a rod or track 12 extending across the upper plate with its ends secured in openings or seats formed in flanges 13 at the upper and lower ends of the plate 1. This

rod has its upper portion cut to form rack teeth 14, as shown in Figs. 1 and 2, for engagement by the teeth of a gear 15 rigidly secured upon a shaft 16 between bearing ears 17 which project upwardly from the tubular body of the carriage at opposite sides of an opening 18 formed therein. It will be readily understood that when the actuating shaft 16 is rotated by grasping either of its heads 19 and 20 the gear will be rotated with the shaft and since the teeth of the gear mesh with the rack teeth formed upon the rod or shaft 12 the carriage will be shifted longitudinally of the body portion of the device and moved 15 either towards the top or bottom of the sheet grasped between the jaws 1 and 2 according to the direction in which the shaft is rotated. A spring 21 is coiled about the shaft between the head 19 and adjacent bearing ear and since 20 the shaft fits loosely in the openings formed in the bearing ears this spring may serve to shift the shaft longitudinally and normally retain a side face of the gear in close contacting engagement with the inner side face of the ear against which the spring bears. Therefore, a frictional engagement will take place between the gear and the bearing ear and, therefore, while the carriage may be easily shifted longitudinally of the rack by turning 25 the shaft it will be held in a set position and prevented from accidentally sliding along the track. A flat tube 22 extends transversely of the tubular body beneath the same and receives a metal strip 23 which projects from 30 the carriage and body portion of the device across the page to be copied and this strip carries an extension 24 which slidably fits thereon and may be moved longitudinally thereof into or out of an extended position according to whether a sheet or body of a 35 standard width is being copied from. Since the tube 22 projects from both sides of the tubular body and is open at both ends, it will be obvious that if a very narrow page is to be copied from the extension 24 may be removed and the strip 23 slid through the tube 22 until it is adjusted to accommodate itself to the width of the sheet.

When the line follower is in use, the handles may be grasped and moved toward each other to spread the jaws or plates 1 and 2 and a sheet of paper or the pages of an opened book inserted between the two jaws. Pressure upon the handles will then be relieved and the sheet of paper or the pages of an opened book will be firmly gripped. The arm or strip 23 and its extension 24 will then extend transversely across the sheet of paper or page of the book and by 55 rotating the shaft the carriage may be adjusted longitudinally of the track to dispose the indicating arm beneath a line of writing or figures across the sheet. As the lines of writing upon the paper or page of the book are copied or verified, the shaft

will be rotated to shift the carriage downwardly to succeeding lines and since the gear has frictional engagement with the inner face of the bearing ear against which the spring 21 bears there will be no danger of the carriage accidentally slipping out of an adjusted position. Therefore, the arm 23 will accurately indicate a line of writing or companion figures provided in columns upon a sheet of paper or page of a book, facilitating accurate copying or verification and there will be no danger of mistakes being made. When no longer needed, the device can be very easily removed by applying pressure upon the handles to swing the jaws 80 apart.

Having thus described the invention, I claim:

1. A line indicator including a support, a rack connected at its ends to the support and spaced therefrom between its ends, a tubular body encompassing the rack and slideable thereon, a guide on the under side of the body extending across the rack, an indicating arm slideable in the guide between the rack and support, and a gear element mounted upon the body and coacting with the rack to move the body and indicating arm over the support.

2. A line indicator including a support, a rack connected at its ends to the support and spaced therefrom between its ends, a tubular body encompassing the rack and slideable thereon and provided with upstanding ears, a guide on the under side of the body extending across the rack, an indicating arm slideable in the guide between the rack and support, a shaft mounted in the said ears, a gear fixed to the shaft and in mesh with the teeth of the rack, and a spring tending to move the shaft and hold the gear in frictional engagement with one of said ears.

3. A line indicator including a support comprising upper and lower plates, pins projecting from the lower plate and loosely engaging the upper plate, springs on the pins exerting a downward pressure on the upper plate, handles projecting from the plates, the lower handle being deflected downwardly at its free end, and adjustable line indicating means mounted upon the upper plate.

In testimony whereof I affix my signature.
OSCAR ERICKSON. [L. S.]
